EDGE CUTTER FOR SHOES

John Hoza, Belcamp, Md.

Application May 13, 1940, Serial No. 334,974
In Czechoslovakia July 30, 1938

13 Claims. (Cl. 12—51)

This invention relates to a machine comprising mechanism for cutting off the edges of shoes in the manufacture thereof, especially overshoes, galoshes and rubber shoes of all sizes.

Heretofore it has been customary to cut off the edges of shoes such as aforesaid by hand, by means of scissors. Such handwork is subject to the usual disadvantage that it is slow. Moreover, it is performed without exactitude, and the bevelling-off is irregular, with the result that shoes 10 with hand-cut edges are often unsightly.

An object of this invention is to provide a machine having mechanism for cutting off the edges of shoes and serving to improve the cutting-off operation both quantitatively and qualitatively.

Another object is to guide and feed the work in an efficient manner.

Another object is to provide mechanism comprising control means for varying the feed of the shoe to an edge-cutting knife during the operation of said mechanism with constant cutting speed so that the curved form of the edge can be varied.

Another object is to provide mechanism comprising means for adjusting the angular relationship between the knife and the work so that the bevel of the edge can be regulated and will be cut with overall uniformity.

Another object of the invention is to provide edge-cutting means so operable, adjustable and controllable that a wide variety of shoes can be turned out.

Other objects of the invention will appear from the following specification and claims.

The invention will now be described by way of example with reference to the accompanying drawing in which:

Fig. 1 is a sectional side elevation of the edge-cutting mechanism.

Fig. 2 is an elevation, partly in section, looking towards the left hand end of the assembly denoted generally by A in Fig. 1.

The edge-cutting mechanism comprises, on the one hand, an assembly for performing the feed motion applied to the shoe and controlling the length of said motion and, on the other hand, an assembly for operating and adjusting the inclination of the knife. These two assemblies and their functions will now be described.

The machine in which the mechanism shown is incorporated includes a main driving shaft 6 journaled for rotation in bearings (not shown) in the frame of the machine, said shaft being motor driven. A disc 5, a flanged ferrule 7 and an intermediate thrust washer 6¹, made of fibre, are all arranged against one another and embrace the shaft 6. The disc 5 is restrained against rotation with the shaft by a pin 5¹ which engages a recess in the forked arm of a lever 4, 55

said forked arm bearing against the disc 5. The lever 4, at its opposite end, is connected by a rod (not shown) to a control pedal. A control pull-rod 1 is mounted for sliding axial movement in the shaft 6, and a cross-pin 8 extending diametrically through the ferrule 7 passes through a hole in the rod 1 and is guided in longitudinal slots in the shaft 6. The rod 1 is urged and normally maintained towards the left, as viewed in Fig. 1, by a spring 2 arranged in the shaft 6 and pressing against the right-hand end of the rod 1.

There is formed in the surface of the pull-rod 1, near its left-hand end, a recess 9 which has an inclined base and which is engaged by a regulating screw 10 extending through the shaft 6 and retained in place by a safety screw 11. Both of these screws are threaded in an eccentric 3 (Figs. 1 and 2). Screws 13 and 14 connect the eccentric 3 to a carrier flange 12 which is secured fast to the shaft 6. The screw 14 passes through a slot 15 in the eccentric, which therefore is pivotable, to vary its eccentricity to a limited extent, about the screw 13. The shaft 6 passes right through both the flange 12 and the eccentric 3. A small pad or brake block 16, which is seated in the eccentric 3, is pressed by a spring 17 against the shaft 6. The spring 17 bears upon a retaining screw 18 in the eccentric 3. The function of the spring 17 is to maintain the screw 10 against the inclined base of the recess 9 and thus to urge the eccentric 3 to adopt its most central, or least eccentric setting, the actual setting being determined by the axial position of the rod 1. A strap or pulley 19 is journaled on the eccentric 3 and extends laterally therefrom. A post 20 is slidable through the strap 19 and is secured fast to a pivotally mounted body 21 which carries the limb 22 at the end of which is the feed foot 23. The limb 22 receives a vertical reciprocating motion from means not shown but known per se.

When the shaft 6 and eccentric 3 thereon are rotated, the strap 19 and post 20 are caused to rock, the post sliding in relation to the strap during this rocking motion. The result of this action is that a to-and-fro or reciprocatory lateral motion is imparted to the foot 23, which motion combines with the aforesaid vertical reciprocating motion to produce a stepwise feed motion imparted by the foot 23. The amplitude of the reciprocatory lateral motion and therefore the magnitude of the stepwise feed motion are proportional to the stroke of the eccentric 3.

In use of the mechanism described, a shoe B is placed upon a lower arm 39 of the frame and the machine is put in operation. The machine is normally set to give the shoe the customary short feed, which is applied at the beginning and to the curve of the shoe edge. The aforesaid

pedal is not depressed in the normal setting of the machine, and therefore the spring 2 maintains the pull-rod 1 pressed in its endmost position towards the left, in which position the eccentric 3 is maintained in its most central setting by the spring 17, the screw 10 then being at the deepest end of recess 9. That is, the eccentric 3 is set to give the shortest stroke to the strap 19, so that the feed-length imparted by the foot 23 also is shortest.

As soon as the edge is to be cut to a slightly incurving form, the feed is increased. This is effected by depressing the pedal attached to the lever 4. Thus, the lever is turned so that its forked end presses the assembly of shaft-embracing parts 5, 6¹ and 7 towards the right, and the cross-pin 8 transmits this motion to the rod 1, so that the inclined base of recess 9 acts like a cam to displace the screw 10 radially outwards against the pressure of spring 17. Accordingly, the eccentric 3 is pivoted into a setting of greater eccentricity and proportionately increases the length of feed applied by the foot 23 to the shoe edge being cut.

By depressing further, or by relieving more or less the pressure on, the pedal connected to lever 4, the control rod 1 is moved further to the left, or returned more or less to the right, so that the eccentricity of eccentric 3 is increased or decreased and the length or rate of feed is proportionately increased or decreased.

With reference now to the knife operating and adjusting assembly, as shown in Fig. 1, screw gears 24, 25 transmit drive from the main shaft 6 to a crankshaft 26, on one end of which a crank 27 is provided. A pitman 28 driven by the crank 27 has an extension 29 which is connected to one end of a bellcrank lever 30. The length of the entire pitman can be adjusted at will by temporarily slackening the connection between the parts 28, 29. The fulcrum pin 31 of the lever 30 is secured to a lug projecting from a guide-block 32 which is angularly adjustable around a segment 33 secured by screws 34, 35 on the frame of the machine. The other end of lever 30 slidably enters a hole penetrating a cylindrical journal pin turnably mounted in the holder 37 of the knife 38. The holder 37 is guided to reciprocate at an inclination in the angularly adjustable guide-block 32. The extent of angular adjustment of the block 32, and therefore of the inclination of the knife 38, is about 10° to 30°. The setting of the guide-block 32 on the segment 33 is selected, and can be adjusted by means of the holder 37, before the commencement of the operation of the machine, or before work starts upon a different form of shoe requiring a different inclination or bevel of the edge to be cut. The length of the pitman 28, 29 is or may be simultaneously adjusted.

The frame of the machine terminates below in the work-supporting arm 39. To this arm a counter-knife is fastened. The adjustable knife 38 is reciprocated by the crank and pitman acting through the lever 30 and holder 37 and co-operates with the counter-knife to shear the material of the upper at the edge thereof.

The operation and regulation of the feed of the shoe is in no respect dependent upon the actuation of the knife. Accordingly, the feed can be varied at will while the cutting speed remains constant. Thus, the form of the shoe-edge curvature is variable under the operator's control of the pedal-operated lever 4 and parts operated thereby.

The arrangement of the lower work-supporting arm 39 is very advantageous, as it renders possible the cutting-out of edges of wide variety.

Modifications may be made without departing from the scope of the invention hereinafter claimed. For example, instead of varying the inclination of the knife, the arrangement may be such that it is the inclination of the shoe edge which is varied.

10 I claim:

1. Edge-cutting mechanism for shoes, said mechanism comprising a support for a shoe, rotary means, a knife adapted to work in relation to said support, a counter-knife on said support adapted to co-operate with said knife, feed means including a reciprocable shoe-engaging member movable in relation to said support to feed the shoe edge to said knife and counter-knife, a transmission from said rotary means to said member for imparting reciprocating feed motion thereto, control means applied to said rotary means for regulating the amplitude of reciprocation of said motion to vary the extent of feeding thereby, means guiding said knife to cut at an inclination to said shoe edge, and means operated by said rotary means actuating said knife.

2. Edge-cutting mechanism for shoes, said mechanism comprising a support for a shoe, rotary means, a knife adapted to work in relation to said support, a counter-knife on said support adapted to co-operate with said knife, feed means including a reciprocable shoe-engaging member movable in relation to said support to feed the shoe edge to said knife and counter-knife, control means applied to said rotary means for regulating the amplitude of reciprocation of said member to vary the rate of feeding thereby, and means operated by said rotary means actuating said knife to cut said edge at regular overall speed.

3. Edge-cutting mechanism for shoes, said mechanism comprising a rotary drive shaft, a knife, a support for a shoe edge, means operated by said shaft to actuate said knife at an inclination to said support, a feed element for feeding the shoe edge in relation to said knife, means for operating said element comprising an eccentric on said shaft and an operative connection between said eccentric and element, and control means for varying the extent of feeding by said feed element, said control means comprising a rod mounted for axial displacement in said shaft, a manually operable lever for controlling the axial position of said rod, said lever having a forked end, motion-transmitting means on said shaft and connecting said forked end to said rod and a connection between said rod and said eccentric, said connection serving to displace said eccentric to vary its eccentricity on axial displacement of said rod.

4. Edge-cutting mechanism according to claim 3, in which said forked end is formed with a recess and in which said motion-transmitting means comprise a ring abutting said forked end, an annular member connected to said rod and axially displaceable on said shaft, a fibre washer sandwiched between said ring and member, and a projection on said ring engaging said recess to hold said ring against rotation with said shaft.

5. Edge-cutting mechanism according to claim 3, in which said motion-transmitting means include a flanged member on said shaft, a pin connecting said member to said rod and a slot in said shaft through which said pin passes to per-

mit axial displacement of said member on said shaft.

6. Edge-cutting mechanism for shoes, said mechanism comprising a rotary drive shaft, a knife, a support for a shoe edge, means operated by said shaft to actuate said knife, feed means for feeding the shoe edge in relation to said knife, said feed means comprising a shoe-engaging feed element mounted for movement to-and-fro, an eccentric on said shaft and an operative connection between said eccentric and said feed element, and control means for varying the extent of feeding by said element, said control means including an axially displaceable member in said shaft, an inclined device in said member and a connection in said eccentric between it and said member for displacing said eccentric to vary its eccentricity.

7. Edge-cutting mechanism according to claim 6 in which manually operable means associated with said shaft are operatively connected to said axially displaceable member for its displacement in one direction, and in which a spring mounted in said shaft urges said member in the opposite direction.

8. Edge-cutting mechanism for shoes, said mechanism comprising a knife, a support for a shoe edge, feed means for feeding the shoe edge to said knife, a holder for said knife, a guide in which said holder and knife are reciprocable in a direction of cut inclined to said support, means for reciprocating said holder and knife to cut said shoe edge at said inclination, and a segment on which said guide is mounted and is adjustable to vary the inclination of said direction of cut.

9. Edge-cutting mechanism for shoes, said mechanism comprising a rotary drive shaft, a knife, a support for a shoe edge, feed means operated by said shaft for feeding the shoe edge to said knife, a holder for said knife, a guide in which said holder is reciprocable at an inclination to said support, knife-reciprocating means operated by said shaft, said knife-reciprocating means including a lever fulcrumed to pivot on said guide and operatively connected to said shaft and a journal turnably mounted in said holder and slidably engaged by said lever, and means for adjusting the angular relationship of said guide to said support in order to vary said inclination.

10. Edge-cutting mechanism for shoes, said mechanism comprising a main rotary shaft, a support for a shoe whose edge is to be cut, a knife, means guiding said knife for movement at an inclination to said support, a counter-knife thereon co-operating with said knife, knife-driving means for reciprocating said knife in said knife-guiding means, said knife-driving means comprising a crank rotated by said shaft, a pitman of adjustable length operated by said crank, and a lever inter-connecting said pitman and knife, said lever being fulcrumed in said knife-guiding means, a segmental element on which said knife-guiding means is mounted and is angularly adjustable to vary said inclination, a shoe-engaging feed-foot mounted in relation to said support for motion including a to-and-fro feed-motion whereby said shoe edge is fed stepwise to said knife and counter-knife, operating means for imparting said feed-motion to said feed-foot, said operating mechanism comprising an eccentric on and rotating with said shaft, an element embracing and actuated by said eccentric and an operative connection between said

element and said feed-foot, and means for adjusting the extent of said stepwise feed-motion comprising an axially displaceable rod in said shaft, a manually turnable lever for controlling axial displacement of said rod in both directions, a cam device on said rod, a carrier on said shaft to which said eccentric is pivotally attached so that its eccentricity can be varied by pivotal adjustment of the eccentric, and a connection between said cam device and said eccentric for pivotally adjusting it under the control of said manually turnable lever and said rod.

11. Edge-cutting mechanism for shoes, said mechanism comprising a rotary shaft, a support for a shoe whose edge is to be cut, a knife, means guiding said knife for movement at an inclination to said support, a counter-knife thereon co-operating with said knife, knife-driving means operated by said shaft to reciprocate said knife in said knife-guiding means, an element on which said knife-guiding means is mounted and is angularly adjustable to vary said inclination, a shoe-engaging feed-foot mounted in relation to said support for motion including a to-and-fro feed-motion whereby said shoe edge is fed stepwise to said knife and counter-knife, operating means driven by said shaft to impart said to-and-fro feed-motion to said feed-foot, and means applied to the last-stated operating means for adjusting the extent of the to-and-fro motion of said feed-foot.

12. Edge-cutting mechanism for shoes, said mechanism comprising a rotary shaft, a support for a shoe whose edge is to be cut, cutting means operated by said shaft and mounted adjacent said support, a shoe-engaging feed-foot mounted in relation to said support for motion including a to-and-fro feed-motion whereby said shoe edge is fed stepwise to said cutting means, operating means for imparting said feed-motion to said feed-foot, said operating mechanism comprising an eccentric on and rotating with said shaft, an element embracing and actuated by said eccentric and an operative connection between said element and said feed-foot, and means for adjusting the extent of said stepwise feed-motion comprising an axially displaceable rod in said shaft, a manually turnable lever for controlling axial displacement of said rod in both directions, a cam device on said rod, a carrier on said shaft to which said eccentric is pivotally attached so that its eccentricity can be varied by pivotal adjustment of the eccentric, and a connection between said cam device and said eccentric for pivotally adjusting it under the control of said manually turnable lever and said rod.

13. Edge-cutting mechanism for shoes, said mechanism comprising a rotary shaft, a support for a shoe whose edge is to be cut, a knife, means guiding said knife in relation to said support, a counter-knife thereon co-operating with said knife, knife-driving means for reciprocating said knife in said knife-guiding means, said knife-driving means comprising a crank rotated by said shaft, a pitman of adjustable length operated by said crank, and a lever inter-connecting said pitman and knife, said lever being fulcrumed in said knife-guiding means, a shoe-engaging feed-foot mounted in relation to said support for motion including a to-and-fro feed-motion whereby said shoe edge is fed stepwise to said knife and counter-knife, and operating means driven by said shaft to impart said feed-motion to said feed-foot.

JOHN HOZA,
